UNITED STATES PATENT OFFICE.

ALBERT B. PRATT, OF LYNDON, VERMONT.

FIREARM.

1,323,609.

Specification of Letters Patent.

Patented Dec. 2, 1919.

Application filed May 15, 1916. Serial No. 97,475.

To all whom it may concern:

Be it known that I, ALBERT B. PRATT, a citizen of the United States, and a resident of Lyndon, county of Caledonia, State of Vermont, have invented an Improvement in Firearms, of which the following description, in connection with the accompanying drawings, is a specification, like characters on the drawings representing like parts.

10 This invention relates to fire-arms and among other objects provides a simple and effective gun adapted to be carried on and fired from the head of the marksman.

The gun in its broad aspect is similar to 15 the one shown in my issued Patent No. 1,183,492, dated May 16, 1916, modified to include certain features of improvement.

The character of the invention may be best understood by reference to the following 20 description of an embodiment thereof shown in the accompanying drawings, wherein:

Figure 1 is a side elevation of a helmet having a gun mounted thereon embodying 25 the invention; the helmet being shown in position on the head of the marksman;

Fig. 2 is a view partly in plan and partly in horizontal section of the gun with the top plate and cover removed;

30 Fig. 3 is a detail showing the latch at the side of the magazine holding the breech-block retreated;

Fig. 4 is a detail showing the breech-block in position to cock the hammer and 35 the safety member in position to prevent the hammer from striking the firing pin;

Fig. 5 is a vertical, longitudinal section taken on line 5—5 of Fig. 2;

Fig. 6 is a vertical, longitudinal section 40 taken on line 6—6 of Fig. 2;

Figs. 7, 8 and 9 are detail views showing the breech-block in different positions;

Fig. 10 is a vertical, transverse section taken on line 10—10 of Fig. 2;

45 Fig. 11 is a side elevation of the breech-block;

Fig. 12 is a view of the bottom of the breech frame and the track therein;

Fig. 13 is a longitudinal section taken on 50 line 13—13 of Fig. 12;

Fig. 14 is a horizontal section through the firing tube shaft; and

Fig. 15 is a transverse section taken on line 15—15 of Fig. 14.

55 The helmet comprises a body 1 (Fig. 1) having front and rear vizors 3 and 5. An

inner band 7 of leather or other suitable material is detachably secured to the body of the helmet by bolts 9 distributed at suitable intervals. The band may form a part 60 of a cap 11, also of leather or other material and fitting into the body of the helmet. To prevent the top of the helmet from resting upon the head of the marksman, the cap is provided with a lining 13 of leather or 65 other suitable material slitted adjacent the upper edge thereof to receive a take-up strap 15 which may be tightened to cause the lining to closely fit the head of the marksman. The cap including the band and its lining 70 may readily be detached from the helmet and worn as a fatigue cap if desired.

To assist in holding the helmet on the head of the marksman, an apron 16 of leather or other material may be secured to 75 the rear edge of the helmet body and be drawn to embrace the back of his head by a strap 16^a inserted through slits adjacent the lower margin of the apron, said strap having a suitable buckle for the purpose.

To support the gun on the helmet, the latter may be provided with a bedplate 17 (Fig. 2) of steel or other suitable material conforming to the top of the helmet and secured thereto. The plate has a rim 19 80 rising from the edge thereof adapted to receive a flat top plate 21 (Figs. 5, 6 and 10) secured by screws to ears 22 on said rim. Thus there is provided a shallow housing appropriate to contain and protect the gun. 85 A spider plate 23 may be mounted on and secured to the bedplate and be formed to support an elongated receiver 25 of steel or other suitable material fast thereon and extending longitudinally of the helmet.

90 The gun comprises a barrel 27 threaded to a breech frame 29 formed to fit into said receiver. The inward movement of said frame therein may be limited by its engagement with a shoulder 31 (Figs. 2 and 5) 100 formed by a lining 32 at the rear end of said receiver.

To detachably secure the breech frame in said receiver, a sleeve 33 is provided beneath the barrel adapted to be rotatively adjusted 105 in straps 35 secured to said barrel to cause a pair of lugs 37 thereon to enter corresponding slots 39 in the spider and bedplates. To facilitate turning the sleeve for this purpose, an arm 41 is provided at the outer end 110 thereof. When this arm depends downward it shows that the lugs are in active engage-

- 2
- ment with their slots. The sleeve may contain a cocking pin 43 to thrust the breech-block away from the barrel as more fully hereinafter described.
- 5 The breech frame 29 (Fig. 12) has an open bottom provided with seats 47 adjacent the ends thereof adapted to detachably receive a track 49 comprising guide rails 53 and 55 projecting upward into said frame.
- 10 A breech-block 57 (Figs. 2, 5, 7, 8 and 9) is mounted in said frame and has a pair of grooves (best shown in the cross-section Fig. 10, in which said grooves contain the guard-rails 53 and 55) to slide on said rails and guide the block as it reciprocates in said frame. The breech-block is urged toward the breech chamber by a helical spring 59 (Figs. 2 and 5) having one end seated in a socket 61 threaded to the rear end of said
- 15 breech frame and its opposite end encircling a stud 63 projecting centrally from the rear end of said breech-block. A vent 61^a in the end of the socket will allow gases to escape therefrom. A firing pin 65 (Figs. 7, 8 and 9) is adapted to slide in a bore in the breech-block and is normally urged rearward by a coil spring 67 encircling said pin in said block, but when struck by the hammer its forward end strikes the primer of the cartridge and discharges the same. The firing pin preferably is arranged near one side of the breech-block in order to escape the helical spring which engages said block centrally thereof. A lateral recess 69 in said
- 20 block is adapted to receive cartridges from the magazine as more fully hereinafter described.
- 25 A housing 71 (Figs. 2 and 10) of steel or other suitable material is secured on one of the legs of the spider plate at one side of the breech frame receiver and is formed to receive a cartridge magazine 73 having a spring-pressed plunger 75 therein for automatically feeding the cartridges toward the
- 30 delivery end of said magazine. The magazine communicates with lateral registering apertures in said receiver and breech frame and has in-turned, resilient lips 77 adapted to project through said apertures and support a cartridge partially in said frame in readiness to be delivered to the chamber of the barrel, as well shown in Fig. 10.
- 35 The breech-block is blown back against the resistance of the spring 59 by the gases from the firing of the cartridge, and is promptly thrust forward again by said spring. In the course of its forward movement the front end of the breech-block engages the head of the cartridge and thrusts
- 40 the same from the magazine into the chamber of the barrel. The rails are flush with the entrance to said chamber and contribute to the guidance of the cartridges thereto.
- 45 To further contribute to the guidance of the cartridges and prevent any possibility of
- their blocking the entrance to said chamber, a guide block 77' (Figs. 2 and 12) may be formed in said breech frame and have inclined edges extending from said magazine to said chamber. In the course of the transit of a cartridge from the magazine to the chamber the rounded nose thereof will engage said inclined edges and the cartridge will be properly directed to said chamber without any possibility of its swinging out of axial alignment with said chamber.
- 50 This guide block has a further important advantage since it enables the entrance to the cartridge chamber to be circular instead of elliptical or irregular form. Consequently the chamber may closely embrace the entire circumference of the cartridge shell with the exception of a small notch for receiving the usual spring-pressed extractor 79 (Figs. 2, 7, 8 and 9) on the breech-block.
- 55 At the time of firing, however, the breech-block is forward against the entrance of said chamber and the extractor projects into and substantially fills said notch. Therefore there is no material interruption in the circumferential contact of the entrance of the chamber with the body of the shell. As a result if a shell should burst, it would expend its force in blowing back the breech-block, without any outlet therefor such as would be likely to cause injury to the marksman.
- 60 To fire the gun a hammer 81 (Fig. 2) is pivoted on a post 83 mounted externally of the breech frame receiver on one of the legs of said spider plate. The hammer is urged through registering apertures in said receiver and frame by a helical spring 83 having one end connected to an arm 85 of said hammer and its opposite end connected to a screw 87 having a head engaging a depending wall 89 of a plate 93. The screw 87 is threaded into a nut 95 held by coils of said spring of smaller convolution than the main body of said spring and may be adjusted to vary the tension of the spring as desired.
- 65 To hold the hammer cocked, its hub has a tooth 97 adapted to be engaged by a sear 99 fulcrumed on a post 101 secured to said spider plate. The sear is adapted to be tripped by a trigger 103 projecting rearward therefrom, thereby permitting the spring 83 to cause the hammer to fly forward into the breech frame and strike the firing pin 65 with a sharp blow. The sear is held in its position to lock the hammer by a spring 104 connected to the trigger and to a post 104^a secured on the spider plate.
- 70 Next will be described means operable from the mouth of the marksman for operating the trigger. To this end a fluid-pressure responsive device conveniently in the form of a pneumatic bulb 105 (Fig. 2), is provided, confined between said trigger and a fixed abutment 107 on the bedplate. This
- 75 80 85 90 95 100 105 110 115 120 125 130

bulb is connected to a tube 109 projecting laterally from a hollow bearing 111 (Figs. 2, 14 and 15) mounted on the spider plate. A tube shaft 113 is journaled in said bearing and another bearing 115 on said spider plate adjacent the rim of the bedplate. The tube shaft has a lateral port 117 (Figs. 14 and 15) adapted to communicate with the bulb tube 109 when rocked to one position, and to cut off communication with said tube when rocked to a different position. To prevent leakage between the tube shaft and the bearing 111, stuffing boxes 121 (Fig. 14) are provided at opposite sides thereof.

15 The tube shaft projects outward through an aperture in the bedplate rim 19 and is connected to a firing tube 123 (Figs. 1 and 2) of brass or other suitable material adapted to depend therefrom at one side of the 20 face of the marksman. This tube has a section 125 threaded thereto and adapted to be secured in different positions of adjustment by a lock nut 127, to vary the effective length of the tube to conform to different persons 25 as required. The lower end of the section 125 may be provided with a rubber or other suitable piece adapted to be inserted in the mouth of the marksman. When he desires 30 to fire the gun, it is merely necessary for him to blow through the tube, thereby expanding the bulb 105 and tripping the sear and releasing the hammer.

The firing tube 123 is adapted to be rocked down to a stop 123^a to communicate with the 35 mouth of the marksman in readiness to fire the gun as shown in full lines in Fig. 1, or it may be rocked up to the front vizor 3 to an inoperative position as shown in dotted lines in said figure, and be held by a clip 131 40 on said vizor. When the tube is up in this inoperative position, the port 117 will be cut off from communication with the bulb tube 109 and thus will prevent the bulb from expanding to trip the trigger and fire the 45 gun.

To prevent further any possibility of the firing of the gun by the hammer when the tube is in its inoperative position, a safety device is provided comprising a plate 133 50 (Figs. 2 and 6) adapted to slide along the side of the breech frame receiver adjacent the hammer. This plate has an aperture 135 for registration with the lateral apertures in said receiver and frame to allow the hammer 55 to rock into the frame to strike the firing pin. When the plate is slid rearward, an edge 137 of its aperture will engage the edge of the hammer and prevent the latter from swinging into the breech frame to said pin. 60 To shift the safety member automatically to this position when the firing tube is rocked up to the vizor to inoperative position, the tube shaft 113 is extended beyond its bearing 111 through the aperture in the 65 safety member to the receiver and the end

thereat is squared to receive an arm 139 fast thereon. The end of this arm is adapted to wipe along an incline or cam surface formed on said slide member. As said arm rocks in a clockwise direction it slides along this cam surface and thrusts the safety member rearward automatically, and brings its said edge 137 in a position to intercept the hammer and prevent the same from striking the firing pin. At the end of the rocking movement of the arm 139, it occupies a notch 143 in said safety member to lock the arm and prevent any possibility of inadvertent release of said member.

When the firing tube is rocked down to 80 the mouth of the marksman, the arm 139 is rocked in a contraclockwise direction (Fig. 6) out of the notch 143 and releases the safety member. To automatically shift said member to a position to prevent intercepting the hammer when the arm is thus rocked, said member may be provided with an ear 145 receiving a rod 147 confined against longitudinal movement relatively to said ear by flanges 149 on said rod. This rod 90 projects outward through a hole at the front of the bedplate rim 19 and has a conveniently accessible handle 151. The rod is normally urged forward by a helical spring 153 encircling the same and confined between a 95 fixed abutment 155 on the bedplate and a fixed collar 157 on said rod. Thus when the firing tube is rocked down from inoperative position, the arm 139 will move out of its locking notch 143 and allow the spring 153 100 to shift the safety member forward out of the way of the hammer.

At times it may be desired to lock the hammer in inoperative position independently of the adjustment of the firing tube, 105 as, for example, when the gun is taken apart for cleaning. To accomplish this, the handle 151 may be pressed to push the rod 147 and safety plate rearward beyond its position where locked by the arm 139. To hold 110 the rod 147 in this position, one of its flanges 149 may have a lug 159 projecting therefrom adapted to enter a slot 161 (Fig. 10) in the bedplate on imparting a slight rotation to said rod. On release of the lug from 115 said slot the spring 153 will thrust the safety member forward until the lug flange 149 engages the fixed stop 155.

When the breech-block blows back it serves automatically to cock the hammer. 120 The face of the breech-block adjacent the hammer would rock the latter out as far as the inner surface of the breech frame, but preferably the hammer should be rocked out beyond the breech frame receiver when 125 cocked. This will prevent the hammer from grinding into the face of the breech-block on the forward movement of the latter and will bring the hammer to a position where it will not interfere with the sliding of the 130

4

breech frame from the receiver. To rock the hammer to the position referred to, a V-shaped lever 163 (Figs. 2 and 5) is pivotally mounted on the top of the breech-block 5 and one arm thereof is adapted to engage the inclined surface 165 of a cam member fast on the breech frame in the path of said arm. As the breech-block retreats from the barrel, said arm of said lever will wipe along said inclined surface and rock the lever and thrust its other arm out against the hammer, thereby rocking the latter out beyond the breech frame receiver to its position shown in Fig. 2 where it is caught 10 and held by the sear. The lever 163 may be mounted in a recess on the top of the breech-block and the rocking movements thereof may be limited by a stop shoulder 167.

20 An important feature of the invention relates to means for automatically locking the breech-block in its retracted position after the last cartridge in the magazine has been fired. To accomplish this, the spring-pressed plunger 75 of the magazine may be 25 provided with a finger 169 (Figs. 2 and 3) projecting forwardly therefrom and adapted to advance with the plunger as the cartridges are progressively delivered from the magazine. When the last cartridge has been 30 delivered to the barrel chamber, the end of said finger will engage the side of the breech-block. When the last cartridge has been fired and the breech-block has been 35 blown back, said finger, urged forward by the plunger spring, will project into the path of the breech-block, intercept the same and automatically lock it in retracted position. The cartridge magazine cannot be 40 withdrawn from its housing as long as the plunger finger remains in engagement with the spring-pressed breech-block. To permit the removal of said magazine, a sliding latch 171 (Figs. 2 and 3) is mounted in a pocket 45 173 at one side of the housing. The latch is normally held in retracted position by a spring-pressed lock lever 175 pivoted on and carried by said latch and pressed through registering apertures in the walls 50 of the housing and magazine. The movement of the latch is limited by a pin 177 which slides in a slot in the wall of said pocket. The inner end of the latch when thrust inward is adapted to engage a chamber wall 179 (Figs. 2 and 4) of a recess in the breech-block, and with cam-like action 55 thrust the breech-block slightly away from the plunger finger and transfer the holding of said block from said finger to said latch.

60 Now the empty magazine may be removed and a filled magazine substituted therefor. Then the latch 171 is pulled outward, thereby permitting the lock lever 175 to rock into the registering openings in the magazine 65 and its housing and serve the dual function

of locking the latch in its retracted position and locking the magazine in its housing.

On the withdrawal of the latch, the breech-block is liberated and is thrust sharply forward by its spring and transfers 70 the foremost cartridge of the magazine from the latter into the barrel chamber in readiness for firing.

The bedplate rim has an opening opposite the outer end of the magazine normally 75 closed by a swing door 180 (Fig. 2). The opening is somewhat wider than the end of the magazine and curved walls 181 and 182 connect the rim with the magazine housing to allow plenty of room for the thumb and finger of the hand to grasp the magazine in removing and inserting the same. The operation of the latch and lock lever and the removal and insertion of the magazine may be readily accomplished with one hand 80 85 without removing the gun from the head of the marksman.

The automatic locking of the breech-block in its retracted position on the firing of the last cartridge of the magazine is a desirable 90 feature, since it eliminates the necessity of manually pushing back the breech-block with the cocking pin to bring the breech-block in a position in readiness to transfer the leading cartridge of the full magazine 95 to the barrel chamber. As stated this operation is effected automatically on the release of the latch 171.

Next will be described means for automatically ejecting the empty shells from 100 the chamber of the barrel. To accomplish this the rail 53 referred to, is extended upward somewhat beyond its companion rail 55 to present a shoulder 183 (Figs. 7, 8, 9, 10 and 12). When the breech-block is in its 105 forward position against the entrance of the barrel chamber, the extractor engages a rim of the cartridge shell as shown in Fig. 7. After the firing of the cartridge the breech-block is blown back along its rails and the 110 extractor drags the cartridge along with it until the opposite edge of the rim strikes the rail shoulder 183. This causes the shell to be tilted as shown in Fig. 8, and ejected laterally through registering openings 185 115 (Fig. 2) in the breech frame and its receiver. The breech-block will then move on rearward to its position shown in Fig. 9 in readiness to impel a fresh cartridge forward from the magazine into the barrel 120 chamber.

To form a passage to guide the empty shells from the helmet, partitions 187 and 189 (Fig. 2) are provided projecting upward from the base plate and extending 125 from the frame and receiver apertures 185 to a discharge port 191 in the bed-plate rim 19. A door 193 is hinged to said rim along the upper edge of said port. This door may be automatically opened when the firing 130

- tube is rocked down to the mouth of the marksman in readiness for firing and may be automatically closed when said tube is rocked up to the vizor to its inoperative position. To accomplish this the door is provided with a segmental arm 195 (Fig. 10) projecting inward therefrom and having an elongated slot 196 receiving a finger 197 (Fig. 2) fast on the firing tube shaft 113 referred to. Thus the rocking of this shaft will automatically open and close said door. Preferably the door is not opened wide, but inclines downward somewhat to deflect the discharging shells down from the helmet.
- 15 To facilitate the cleaning of the gun, a brush 199 (Fig. 2) may be provided adapted to be inserted in a case 201 mounted on the bedplate at the side of the breech frame receiver and extending beneath the cartridge 20 magazine. This casing has an enlarged end 203 to accommodate the brush and is adapted to receive a supply of oil for the brush. The stem 205 of the brush projects forward through the neck of the casing and has 25 a handle 207 conveniently accessible at the front of the helmet. The brush may be readily withdrawn from its casing and thrust into the barrel to clean the same as desired.
- 30 To further protect the gun a cover 209 (Fig. 1) may be fitted over the top plate and bedplate rim and may be rounded or slightly domed to contribute to the finished appearance of the helmet. The cover is detachably secured to said rim by spring-pressed clips 210. A hood 211 projects forwardly from the cover to protect the barrel of the gun. The cover may be readily removed and inverted to serve as a cooking pan if 40 desired. In this use the hood will furnish a convenient handle for the pan.
- To facilitate adjustment of the helmet to the head of the wearer to present the barrel at the appropriate elevation for firing, a 45 finder may be provided comprising a slotted guide member 213 (Fig. 1) adapted when in use to be yieldingly held against opposed studs 217 fast in the sides of said hood and adapted to slide along the studs 50 217 when in horizontal position so as to telescope into the helmet when not in use. A sight or index 219 is adapted to slide along this guide member and may be held in different positions of adjustment by a set screw 55 221. The guide member may be graduated in inches and the index held opposite any of the graduations desired. Knowing the distance from the axis of the barrel of the gun to a line connecting his eyes, the marksman 60 may adjust the index to a point on the guide corresponding to this distance and then tilt the helmet up or down as required until the index is on a level with his eyes. Then the gun is positioned properly for firing and the finder may be rocked up and

retreated back over the barrel of the gun into inoperative position.

To facilitate the proper vertical alinement of the barrel of the gun with the face of the marksman, a nub 223 (Fig. 1) may be provided on the under face of the front of the vizor directly over the nose of the marksman. In putting on the helmet, the thumb may naturally simultaneously engage said nub and the nose, and thereby indicate the proper adjustment thereof.

When it is desired to clean the gun, the barrel, breech frame, breech-lock, its main spring and guiding track may be readily removed as a unit from the receiver without 70 removing the helmet from the head of the wearer. To accomplish this, it is merely necessary to turn the sleeve containing the cocking pin sufficiently to release the lugs on said sleeve from the lock slots and then by 80 grasping the barrel said parts may be readily pulled out from said receiver. The main spring socket 61 may be readily unscrewed from the breech frame to remove 85 the main spring and the track may be readily taken out from its seats in the bottom of said frame and the breech-block removed therefrom. Thus all parts which are subjected to the hardest use are readily accessible for removal, replacement, 90 cleaning and repair.

The gun described may be easily and readily fired from the head of the marksman leaving his hands free for other purposes as desired. The gun is strong, simple and 100 compact in construction, safe and not liable to get out of order.

While the gun is shown herein as mounted on a helmet, it will be understood that certain features thereof are not limited to 105 this purpose, but are applicable to guns in general.

Having described one illustrative embodiment of the invention without limiting the same thereto, what I claim as new and desire 110 to secure by Letters Patent is:

1. In a gun, the combination of a breech-frame, a breech-block slidable therein, a magazine, a track below said breech-block having plural projections engaging slots in said 115 breech-block, and providing between them a track substantially parallel with the axis of the barrel of the gun on and along which the cartridges may travel when passing from said magazine to said breech-block, said 120 track providing a projection for engagement with the cartridge shell during retraction of said breech-block to effect ejection of said shell.

2. In a gun, the combination with a barrel, of a breech-frame, a breech-block, a hammer, a magazine, a spring-pressed plunger therein having a finger projecting therefrom for automatically locking said lock in inoperative position, and a latch 130

- member independent of the hammer for holding said block in inoperative position to permit the removal of the magazine from the gun.
5. 3. In a gun, the combination with a barrel, of a breech-block, a hammer, a magazine having a spring-pressed plunger therein for automatically holding said block re-treated after the last cartridge in said mag- 65
10 azine has been fired, and substitute means independent of the hammer to hold said block in said position to allow removal of said magazine.
4. In a gun, the combination with a barrel, of a breech-frame, a block therein, a hammer, a magazine, a carrier therefor, a spring-pressed plunger in said magazine having an element for automatically locking said block in inoperative position, means 70
15 for locking said magazine in said carrier, and a latch member 171 independent of the hammer having provision for releasing said magazine and provision for holding said block in inoperative position to permit the 75
20 removal of said magazine from its carrier.
5. In a gun, the combination with a barrel, of a breech-block having a firing pin, a hammer coöperating with said pin, and a coil spring for actuating said hammer hav- 80
30 ing a portion of smaller convolution than the main body of the spring, a nut held by said portion, and a screw member threaded in said nut to vary the tension of said 85
25 spring.
35. 6. In a gun, the combination with a bed-plate, of a barrel, a breech frame, a breech-block therein having a firing pin, a cocking rod, a sleeve containing the same, and a pro- 90
30 jection on said sleeve for engagement with 95
40 said bedplate for limiting movement of said breech frame relatively to said bedplate.
7. In a gun, the combination with a bed-plate, of a barrel, a breech frame connected to said barrel, a breech-block, a hammer, a 100
45 sleeve carried by said barrel having a pro-
jection for engagement with said plate to secure said breech frame thereto, and a rod mounted in said sleeve for thrusting back said breech-block to cock said hammer.
50. 8. The combination with a bedplate, of a receiver thereon, a barrel, a breech frame connected thereto adapted to slide into said receiver, and means detachably to connect said frame with said receiver.
55. 9. The combination with a bedplate hav- 105
50 ing a receiver thereon, of a barrel, a breech frame connected to said barrel for insertion in said receiver, a breech-block adapted to slide in said frame, and means detach- 110
60 ably to connect said frame with said receiver.
10. The combination with a support, of a receiver thereon, a barrel, a breech frame connected thereto for insertion into said re- 115
65 ceiver, means to detachably connect said frame with said receiver, a cartridge maga- 120
70 zine mounted on said support at one side of said receiver, and firing mechanism mounted on said support at the opposite side of said receiver.
11. The combination with a support, of a receiver thereon, a barrel, a breech frame, a breech-block adapted to slide in said frame, means detachably to secure said frame in said receiver, a cartridge magazine mounted 75
80 on said support at one side of said receiver, and a firing mechanism coöperating with said breech-block and mounted on said sup- 85
75 port at the opposite side of said receiver.
12. The combination with a support, of a receiver thereon having lateral apertures therein, a barrel, a breech frame connected thereto for insertion in said receiver, a cartridge magazine on said support at one side of said receiver and communicating 90
85 with one of the apertures in the latter, and a firing mechanism on said support at the opposite side of said receiver operating through another aperture therein.
13. The combination with a support, of a receiver thereon, a barrel, a breech frame for insertion into said receiver, a breech-block adapted to slide in said frame and having a firing pin, a cartridge magazine at one side of said receiver, and a firing mecha- 95
90 nism at the opposite side of said receiver, in-
cluding a hammer adapted to project into 95
100 said receiver and strike said firing pin.
14. The combination with a receiver, of a barrel, a breech frame for insertion in said receiver, a breech-block in said frame, a cartridge magazine at one side of said receiver, and a firing mechanism coöperating with the firing pin at the opposite side of 105
100 said receiver.
15. The combination with a receiver hav- 110
105 ing lateral apertures, of a fixed barrel, a breech frame connected to said barrel for in-
sertion into said receiver, a cartridge maga- 115
110 zine communicating with one of said lateral apertures, a breech-block in said frame, and means coöperating therewith to eject empty shells through another of said lateral apertures.
16. The combination with a support, of a receiver thereon, a barrel, a breech frame connected to said barrel for insertion into said receiver, a cartridge magazine on one side of said receiver, an empty shell receiv- 120
115 ing chamber on the opposite side of said receiver, and a breech-block in said frame for ejecting empty shells into said chamber.
17. The combination with a bedplate, of a receiver thereon, a barrel, a breech frame connected to said barrel for insertion into 125
120 said receiver, a magazine on said plate to deliver cartridges to one side of said receiver, and a chamber on the opposite side

of said plate to receive shells ejected from the said receiver.

18. The combination with a bedplate, of a receiver on said plate having an aperture therein, a barrel, a breech frame connected thereto for insertion into said receiver, a breech-block in said frame having a firing pin, a hammer mounted on said plate outside of said receiver and adapted to project through said aperture to strike said pin, and a safety member to slide along said receiver and prevent said hammer from striking said pin.

19. The combination with a barrel, of a breech frame, a breech-block therein having a firing pin, a firing mechanism including a tube adjustable to operative and inoperative positions, and a safety member controlled by said tube automatically to prevent said hammer from striking said pin when said tube is in inoperative position.

20. The combination with a barrel, of a breech-block having a firing pin, a hammer to strike said pin, a sear for said hammer, means including a blow tube to cause said sear to trip said hammer, and a safety member controlled by said tube to lock said hammer.

21. The combination with a barrel, of a firing mechanism including a hammer and a mouth tube adjustable to operative and inoperative positions, and a safety device for automatically locking said hammer when said tube is in inoperative position.

22. The combination with a barrel, of a firing mechanism including a hammer and a blow tube adjustable to operative and inoperative positions, a safety member and an element on said tube to shift said member to lock said hammer when said tube is in inoperative position.

23. The combination with a barrel, of a firing mechanism including a hammer and a blow tube to operate the sear to release said hammer, a safety member having a cam surface, and an element on said tube to engage said surface to shift said member to prevent said hammer from operating to fire the gun.

24. The combination with a barrel, of a breech-block, a firing mechanism therefor including a hammer and a firing tube adjustable to operative and inoperative positions, a safety member, means to shift the same to a position to lock said hammer on adjustment of said tube to inoperative position, and means to lock said member in said position.

25. The combination with a barrel, of a breech-block, a firing mechanism therefor including a hammer, means to operate the sear to release said hammer adjustable to operative and inoperative positions, and a safety member to prevent said hammer

from firing the gun when said means is in inoperative position.

26. The combination with a barrel, of a breech-block having a firing pin, a firing mechanism including a hammer and a blow tube adjustable to operative and inoperative positions, a safety member, means to shift said member to a position to limit said hammer and prevent the same from striking said pin when said tube is in inoperative position, and means to shift said member further to limit movement of said hammer.

27. The combination with a receiver, of a barrel, a breech frame connected thereto for insertion into said receiver, a breech-block in said frame, a hammer adapted to project through said receiver and frame toward said block, and safety means to prevent said hammer from entering said frame, to allow removal of the latter from said receiver.

28. The combination with a receiver, of a barrel, a breech frame connected thereto for insertion into said receiver, a breech-block in said frame, a hammer adapted to project through said receiver and frame toward said block, a safety member, means to adjust said member to prevent said hammer from reaching said block, and means to adjust said member to prevent said hammer from entering said frame.

29. The combination with a receiver, of a barrel, a breech frame connected thereto for insertion into said receiver, a breech-block in said frame, a hammer adapted to project through said receiver and frame toward said block, a safety member, means to shift said member to prevent said hammer from reaching said block, and means independent of said last named means to shift said member to prevent said hammer from entering said frame.

30. The combination with a receiver, of a barrel, a breech frame connected thereto for insertion into said receiver, a breech-block in said frame, a hammer adapted to project through said receiver and frame toward said block, a safety member, and substitute devices to shift said member to prevent said hammer from firing the gun.

31. The combination with a receiver, of a barrel, a breech frame connected thereto for insertion into said receiver, a breech-block in said frame, a hammer adapted to project through said receiver and frame toward said block, a safety member, means to shift said member to a position to prevent said hammer from firing the gun, and means to lock said member in said position.

32. The combination with a receiver, of a barrel, a breech frame connected thereto for insertion into said receiver, a breech-block in said frame, a hammer adapted to project through said receiver and frame toward said block, a safety member, a rod to

shift said member to a position to prevent said hammer from firing the gun, means to lock said rod in said position, and spring means tending to shift said member from 5 said position.

33. The combination with a barrel, of a breech-block, and a firing mechanism therefor including a hammer, a sear, a trigger to trip said sear, a blow tube to operate said 10 trigger adjustable to operative and inoperative positions, and valve means automatically to close said tube when in inoperative position.

34. A gun having a firing mechanism comprising a hammer, and means to operate said hammer including a tube rotative to operative and inoperative positions, and valve means automatically to close the passage in said tube to prevent operation of said hammer thereby when said tube is in inoperative 20 position.

35. A gun having a firing mechanism comprising a hammer, a trigger, a fluid-pressure responsive member to trip said trigger, a 25 blow tube adjustable to operative and inoperative positions, and means providing communication between said tube and device only when said tube is in operative position.

36. In a gun, the combination with a barrel, of a breech frame, a chamber to receive empty shells from said frame, a door for 30 said chamber, a firing member adjustable to operative and inoperative positions, and 35 means automatically to open said door when said member is shifted to operative position.

37. In a gun, the combination with a barrel, of a breech frame, a chamber to receive 40 empty shells therefrom, a door for said chamber, a firing mechanism including a member adjustable to operative and inoperative positions, and means automatically to open and close said door when said member is adjusted to said positions.

38. The combination with a head gear, of a gun mounted thereon, and a firing tube adapted to project from said gun to the mouth of the marksman, and means to vary 50 the effective length of said tube.

39. The combination with a head gear, of a gun mounted thereon, and means to fire the gun including a sectional tube extending from said gun to the mouth of the marksman, one of said sections being adjustable 55 relatively to the other to vary the effective length of the tube.

40. The combination with a helmet having a vizor, of a gun mounted on said helmet, 60 and means to fire said gun including a tube adjustable to and from said vizor and the mouth of the marksman, a chamber to receive empty shells having a door, and means automatically to close said door when said

tube is adjusted to said vizor and to open 65 said door when said tube is adjusted to the mouth of the marksman.

41. The combination with a support, of a receiver mounted thereon, a barrel, a breech frame connected thereto for insertion in said receiver, a magazine to deliver cartridges to said frame, and a chamber adjacent said receiver to receive a device for cleaning said barrel. 70

42. The combination with a support, of a receiver thereon, a barrel, a breech frame connected thereto for insertion into said receiver, a chamber adjacent said receiver having an oil well therein and adapted to receive 75 a brush for cleaning said barrel. 80

43. The combination with a head gear, of a gun mounted thereon, a receiver on said head gear, a barrel, a breech frame connected thereto for insertion into said receiver, and a housing adjacent the latter to receive 85 a brush for cleaning said barrel.

44. The combination with a barrel, of a breech frame, a breech-block therein, a hammer outside of said frame, and rocking means carried by said block automatically 90 to thrust said hammer from said frame on retreat of said block from said barrel.

45. The combination with a barrel, of a breech frame having a cam thereon, a hammer mounted externally of said frame, and 95 a member on said block coöperating with said cam to thrust said hammer from said frame on retreat of said block from said barrel.

46. The combination with a barrel, of a breech frame, a breech-block therein, a cam fixed on said frame, a hammer outside of said frame, and a lever pivoted on said block coöperating with said cam to thrust 100 said hammer from said frame on retreat of 105 said block from said barrel.

47. The combination with a head gear, of a gun mounted thereon, and means including a finder to assist in varying the elevation of said gun. 110

48. The combination with a head gear, of a gun mounted thereon, and a finder depending from said gun in front of the face of the marksman to assist determination of the elevation of said gun. 115

49. The combination with a head gear, of a gun mounted thereon having a barrel projecting forwardly beyond said head gear, a cover for said barrel, and means depending from said barrel to assist in varying the 120 elevation of said barrel.

50. The combination with a support, of a receiver 25 thereon, a magazine holder 71 on said support, a cartridge magazine 73 adapted for insertion into said holder, 125 a firing mechanism on said support, a barrel 27, a breech frame 29 connected thereto adapted for insertion into said receiver, a

track 49 in said frame, and a breech-block 57 adapted to slide on said track, said breech frame, track and block being removable as a unit from said receiver.

5 51. The combination with a support 17, of a receiver 25 thereon, a cartridge magazine 73 on said support at one side of said receiver, a firing mechanism on said support at the opposite side of said receiver, a 10 barrel 27, and a breech frame 29 fitting into and removable from said receiver.

15 52. A gun comprising a firing mechanism including a hammer 81, a breech-block 57 having a firing pin 65, a safety device 133 movable between said pin and hammer to prevent said hammer from striking said pin, means 99, 103, 113, 123, to operate said hammer, and means 139 to control said safety device.

20 53. In an automatically reloading magazine gun, the combination with a barrel and breech-block, of a magazine located at one side of the axis of said barrel, and firing mechanism at the opposite side of the axis 25 of said barrel.

25 54. In an automatically reloading magazine gun, the combination with a fixed barrel, of a breech-frame fixed during the operation of the gun, a breech-block slidable 30 in said breech-frame, ejecting means car-

ried by said breech-block, a hammer, cocking means operated by said breech-block and including means for moving the hammer entirely out of the range of movement of the breech-block, a magazine for feeding cartridges in front of said breech-block when the latter is in retracted position, and resilient means opposing rearward movement of said breech-block while actuating forward movement thereof. 35 40

55. In an automatically reloading magazine gun, the combination of a barrel, a breech-block alined with said barrel, a cartridge magazine located on one side of the axis of said barrel, a discharge aperture for 45 ejection of cartridge shells on the opposite side of the axis of said barrel, a firing-pin carried by said breech-block, and firing mechanism coöperating with said firing-pin located on the opposite side of the axis of 50 said barrel from said magazine, whereby the gun is substantially balanced about the axis of said barrel.

In testimony whereof, I have signed my name to this specification.

ALBERT B. PRATT.
